UNITED STATES PATENT OFFICE.

ANDREW W. STEIGER, OF NEW YORK, N. Y., ASSIGNOR TO UNION TYPEWRITER COMPANY, OF JERSEY CITY, NEW JERSEY, A CORPORATION OF NEW JERSEY.

TYPE-WRITING MACHINE.

No. 899,848.

Specification of Letters Patent. Patented Sept. 29, 1908.

Application filed January 29, 1906. Serial No. 298,469.

To all whom it may concern:

Be it known that I, ANDREW W. STEIGER, citizen of the United States, and resident of the borough of Manhattan, city of New York, in the county of New York and State of New York, have invented certain new and useful Improvements in Type-Writing Machines, of which the following is a specification.

10 My invention relates more especially to the ribbon mechanism of typewriting machines.

15 Stated generally, the main object of the invention is to provide simple and efficient means whereby any of a plurality of inking surfaces having different characteristics may be brought to position to coöperate with the types.

20 Other objects of the invention will appear hereinafter.

In carrying out my invention I provide a 25 ribbon carrier or guide which is located between the ribbon spools and through which the ribbon passes in such a way as to present one side of the ribbon for coöperation with the type faces, and so that as the ribbon is fed back and forth between the ribbon spools the type impressions will describe a path longitudinal of the ribbon and along one portion of the width of the ribbon. The ribbon carrier or guide is so constructed that it may be reversed or turned when desired, so as to 30 present the other side or face of the ribbon to the types, and when the carrier has been thus 35 reversed the type impressions will describe a path longitudinal of the ribbon and along another and different portion of its width during the operation of the machine. It will readily be understood that if the ribbon is divided into longitudinal stripes having different 40 characteristics, as for example different colors, one color will be operated on by the types when one side or face of the ribbon is presented to them and another color will be 45 operated on by the types when the opposite side or face of the ribbon is presented to them.

In the preferred embodiment of my invention illustrated herein I have shown a ribbon carrier or guide applied to a front-strike typewriting machine, said carrier or guide normally maintaining the ribbon away from the printing point and being combined with

means for giving it a reciprocatory movement to and from the printing point during 55 printing operations. This type of ribbon carrier is commonly called a ribbon vibrator. In front-strike writing machines having a ribbon vibrator the ribbon which is employed is usually quite narrow and in many styles of 60 front-strike typewriting machines said ribbon is fed back and forth in only one direction, that is longitudinally, so that the type impressions describe a single line longitudinally of the ribbon. 65

My invention provides a ready means for causing the type impressions to describe a plurality of paths longitudinal of the ribbon, thereby exhausting the ribbon surface more uniformly and thoroughly. It will be understood that this latter advantage is applicable to a ribbon which is of uniform character throughout, although I have shown in the drawings a ribbon having a plurality of fields or longitudinal stripes of different 75 characteristics or colors commonly called a polychrome ribbon, and my invention is especially advantageous when employed in connection with such a ribbon.

To the above and other ends which will 80 subsequently appear, my invention consists in the features of construction, combinations of devices and arrangements of parts herein-after fully described and particularly pointed out in the claims. 85

In the accompanying drawings, Figure 1 is a vertical longitudinal sectional view, taken about centrally, of so much of a typewriting machine as is necessary to a clear understanding of my invention. Fig. 2 is an enlarged side elevation of the ribbon carrier or vibrator and a part of its supporting bracket. Fig. 3 is a fragmentary front elevation of the machine. Fig. 4 is a fragmentary top plan view of the machine. Fig. 5 is an enlarged 90 top plan view of a part, herein-after called the guide part, of the ribbon carrier or vibrator. Fig. 6 is an enlarged longitudinal sectional view of the ribbon carrier or vibrator and its supporting bracket. Fig. 7 is an enlarged 95 perspective view of the supporting bracket of the ribbon carrier or vibrator. Fig. 8 is an enlarged perspective view of a part, herein-after called the holding part, of the ribbon carrier or vibrator. Fig. 9 is an enlarged 100 perspective view of the guide part of the rib- 105

bon carrier or vibrator and of the member which connects said part with the holding part of said carrier or vibrator, said connecting member being hereinafter called a trunnion plate.

Referring now to the drawings, and more especially to Figs. 1 and 3, the main frame of the machine is shown as comprising a base 1 supporting corner posts 2 which in turn support a top plate 3. Pivoted at 4 in the rear of the base are key levers 5, each key lever being provided with a restoring spring 6. Each key lever is connected by a link 7 with a sub-lever 8 pivoted at 9 in a hanger 10, said sub-lever being connected by a link 11 with a type bar 12 pivoted at 13 in a hanger 14 secured by a screw 15 to a stationary support 16. The type bars are segmentally arranged and are normally supported at their free ends 15 by a stationary segmental type rest 17, and are adapted to coöperate with the front face of a cylindrical platen 18. Said platen is diagrammatically illustrated herein, but it is to be understood that it is suitably mounted 20 in a platen carrier (not shown) which is adapted to be moved back and forth across the top plate during the operation of the machine, said platen carrier being connected by a strip 19 with a spring drum 20 which tends 25 constantly to draw the platen 18 and platen carrier leftward across the top plate. The leftward movement of the platen is controlled by suitable escapement devices (not shown) which have connections including 30 depending rods 21 (Fig. 3) with a universal bar 22 extending from side to side of the machine beneath the series of key levers. The universal bar is adapted to be actuated by the key levers 5 during the printing operations 35 to cause the escapement devices to co-operate to permit the platen to move a letter space distance at a time leftward across the top plate. The features above referred to and not illustrated are common in the art 40 and will be understood without further description. The general framework of the machine and the type actuating mechanism herein illustrated and briefly described above are not claimed herein as they are the invention 45 of Oscar Woodward.

Ribbon spools 23 arranged vertically beneath the top plate 3, one at each side of the machine and forward of the platen, are provided with a ribbon 24 which is wound upon 50 said spools and has its ends secured thereto. As herein shown the ribbon 24 is divided longitudinally into fields *a* and *b* of different characteristics; that is to say, the field *a* may be of one color, such as black, and the field *b* 55 may be of another and different color, such as red, or the field *a* may be copying ribbon and the field *b* record ribbon, for example. The ribbon 24 may be fed longitudinally from either spool to the other by any suitable 60 means, one such means being shown in the

drawings. Each ribbon spool 23 is secured on the forward end of a horizontally disposed shaft 25, said shaft being journaled in lugs 26 and 27 depending from the top plate 3. The rear end of the shaft 25 is provided with a 70 beveled pinion 28 (Figs. 1 and 4), which is adapted to mesh with a beveled pinion 29 secured on a rotary driving shaft 30, the latter extending from side to side of the machine beneath the top plate and being journaled in 75 lugs 31 depending from the under side of said top plate. Rotary movement is transmitted to the driving shaft 30 by beveled pinions 32 and 33, the pinion 32 being operatively connected with the driving shaft and the pinion 33 with the carriage spring drum 20. It will be understood that both ribbon spools are provided with similar gear trains which are adapted to be actuated from driving pinions 80 32 on the driving shaft 30. The driving 85 shaft 30 is adapted to be moved to and fro endwise manually or by any suitable automatic means without displacing the pinion 32 from mesh with its coöperating pinion 33 by reason of the pin and slot connection 33^a 90 between the shaft 30 and the pinion 32; and it will be further understood that the longitudinal position of said shaft determines which driving pinion 29 will be in mesh with its coöperating pinion 28 and which ribbon 95 spool will be turned to wind the ribbon thereon.

Midway between the ribbon spools, the ribbon is threaded through a vertically disposed ribbon carrier or vibrator which is arranged between the ribbon spools and the platen. I have illustrated my improved vibrator as comprising two parts, a ribbon guide part 34 and a vibratory holding or supporting part 35 upon which the ribbon guide 100 part is mounted, these parts being best illustrated in Figs. 8 and 9. The guide part or plate 34 is preferably formed of sheet metal, the body portion 36 being cut away in the center, as indicated at 37. Arms 38 and 39 105 are formed at each side of the body portion of the guide plate, said arms being first bent forwardly from the face of the body portion and thence inwardly towards the middle of the guide plate. The arms are thereby 110 given an angled form, one part of each arm 38 extending at right angles to the body portion, said part being indicated by the reference character 38^a and the other part extending inwardly parallel to the body portion, the 115 latter part being indicated by the reference character 38^b. The corresponding parts of each arm 39 are indicated by the reference characters 39^a and 39^b. The companion arms at each side have their portions 38^b and 39^b flush with each other, said portions terminating in diagonal edges 38^c and 39^c, said edges being slightly separated and thereby forming a diagonal slot 40 which is designed 120 to admit the ribbon to a guide slot 41 formed 125

longitudinally of the portions 38^a and 39^a of the companion arms at each side of the guide plate.

As best shown in Fig. 5, the flattened inner end 42 of a trunnion 43 is suitably secured, as by rivets 44, at each side of the body portion 36 of the slotted guide part or plate 34, said trunnions 43 projecting laterally from the sides of the guide plate about midway of the length of the latter. The left-hand trunnion 43 is formed at its outer end with a flat extension 45 which is perforated at 46 for a purpose presently to be described. The trunnions 43 are journaled on a U-shaped connecting member or trunnion plate 47, the base 48 of said trunnion plate extending normally beneath the guide part 34, and the arms 49 of said trunnion plate extending upwardly at either side of said guide part 34, said arms 49 terminating in enlarged perforated ends 50 which serve as the bearings for the trunnions 43. The guide part 34 of the vibratory ribbon carrier is supported, through the connecting member 47, on the holding part 35 of said carrier or vibrator, which holding part 35, as shown in Fig. 8, comprises a body portion 51 and a stem 52 extending rearwardly and downwardly from said body portion. The holder 35 is preferably formed of a single piece of sheet metal. The upper portion of the body 51 is provided with a type opening 53. Beneath said type opening and extending longitudinally of the body is a guide slot 54, the upper portions of the sides whereof are curled or bent rearwardly to provide beveled edges 55. Extending upwardly and outwardly from the lower end of said guide slot is a spring tongue 56, the upper end of which is hooked or bent rearwardly, as indicated at 56^a. At either side of the spring tongue 56, the metal of the body 51 is cut and pressed outwardly to form supporting lugs 57 and above these lugs 57 the metal is pressed rearwardly to provide elongated contacts or track-ways 58.

As will be understood from a consideration of Figs. 1, 2, 3 and 6, the base 48 of the connecting member 47 rests on the supporting lugs 57 of the holding part 35, said base being confined between the face of the body 51 and the spring tongue 56, which tongue normally presses the connecting member 47 and through it the guide part 34, against the holding part 35 of the ribbon carrier. The hook-like portion 56^a of the spring tongue prevents the accidental withdrawal of the member 47 from its place between the spring tongue 56 and the face of the body 51. The stem 52 of the holding part 35 is bifurcated to form depending arms 52^a which are curled as indicated at 52^b to receive a cross-pin 59 which is engaged by one of the members of the actuating mechanism, presently to be described.

65 The ribbon carrier or vibrator is supported

on a bracket 60 which, as shown clearly in Fig. 7, is preferably U-shaped, comprising arms 61 jointed at the top by a connecting web 62. The arms 61 are curved first rearwardly from the web 62 and then forwardly and terminate at the bottom in laterally projecting ears 63 perforated at 64 to receive securing screws 65 which screw into threaded openings in the back of the type bar support 16 at each side of the middle of said support, as clearly shown in Fig. 3. The upper portion of the web 62 has secured in it a guide screw 66 which projects forwardly through the guide slot 54 in the holding part 35 of the vibrator. The beveled edges 55 of said guide slot engage the beveled head of the screw 66 and the track-ways 58 contact with the face of the web 62 of the bracket, thereby serving to guide and control the vibrator as it is reciprocated up and down between the arms 61 of the latter, the track-ways 58 sliding up and down on the front face of the web 62 of said bracket.

Referring now to the vibrator actuating mechanism, this is best shown in Figs. 1, 3 and 4. The sides 61 of the bracket 60 are formed with holes 67 which receive a cross-rod 68 which serves as a pivot for a bell crank lever 69, the forwardly projecting arm 69^a whereof engages the cross-pin 59 at the lower end of the vibrator. The bell crank lever 69 is disposed midway of the length of the cross rod 68, said rod being provided with sleeves 70 (Fig. 4) at either side of the lever 69 to prevent lateral displacement of the latter. 100 The downwardly projecting arm 69^b of the lever 69 is pivotally connected at 71 to a rearwardly extending link 72, the rear end of said link being pivotally connected at 73 with the upwardly extending arm 74 of a bell crank lever 75. The bell crank lever 75 is formed with a hub 76 (Fig. 3), which hub surrounds a stationary pivot rod 77 extending from side to side of the machine and having its ends secured in lugs 78 projecting upwardly 110 from the sides of the base 1. Collars 79 are secured to the rod 77 at either side of the bell crank lever 75, said collars preventing lateral displacement of said lever. The forward end of the horizontally disposed arm 75^a of the bell crank lever 75 is adjustably connected by a downwardly extending wire rod 80 with the universal bar 22. As indicated in Fig. 3, the upper edge of the ribbon lies normally below the printing point, said ribbon being adapted, through the above described connections, to be moved upwardly to cover the printing point with its upper portion when a key lever is operated to depress the universal bar. 125

For conveniently reversing or turning the ribbon guide part 34 of the vibrator, I provide a crank rod 81 (Figs. 3 and 4). The inner end of the crank rod is bifurcated to embrace the flat extension 45 of the left-hand 130

trunnion 43 and is pivotally connected therewith by a pin 82 which passes through the hole 46 and has its ends engaging the arms 81^a of the bifurcated portion of the rod 81. 5 The inner portion of the rod 81 is off-set, as indicated at 83, in order that when the guide part of the vibrator is reversed, the ribbon will not be interfered with by the rod 81. The outer or left-hand end portion of the 10 guide rod 81 passes through an opening 84 in a guide bracket 85, said bracket being secured to the top plate by a screw 86. The outer end of the crank rod 81 is provided with a crank arm 87 terminating in a handle or 15 finger piece 88 which may be turned to manipulate the rod and reverse the guide part of the vibrator. During the vibratory movements of the ribbon carrier, the crank rod 81 will move up and down with said carrier, the bearing opening 84 in the bracket 85 being enlarged as indicated in Fig. 4 to permit of the free vibration of said crank arm.

From an inspection of Figs. 3 and 9 it will be observed that the pivotal center on which 25 the ribbon guide 34 turns (the trunnions 43) is substantially coincident with the longitudinal axis of the ribbon where it passes through the guide and that therefore the edge of the ribbon which is uppermost bears the 30 same relation to the vibrator and to the printing line whether the printing field *a* or *b* is in use.

Referring now to the operation of the devices hereinbefore explained and assuming 35 that it is desired to employ a two-color ribbon, as illustrated in the drawings, said ribbon is wound upon the spools in the usual manner and is then threaded in the guide part 34 of the carrier or vibrator. In order 40 to properly thread the ribbon, its lower edge is first pulled down behind the upper prong portions 39^b of the upwardly extending arms 39, and after the upper edge of said ribbon has passed by the points or lower free ends of 45 the portions 38^b it is backed up or straightened behind the downwardly projecting portions 38^b of the arms 38. By this operation it will be noted the ribbon has been passed 50 through the diagonal slots 39^c and arranged in the vertically disposed slots 41. In this position the printing portion of the ribbon, or that portion in the guide, is, as will be understood from an inspection of Figs. 1, 3 and 4, vertically disposed in front of the 55 platen and with the upper edge normally maintained just below the printing line. The ribbon as it leaves the spools and extends towards the vibrator is horizontally disposed, so that between the vibrator and each spool it is given a quarter turn or twist, as indicated at 89 (Fig. 1). In mounting the 60 ribbon on the spools and in threading it in place, it is preferable to arrange the ribbon as shown in the drawings with the black half 65 or stripe *a* of the ribbon towards the rear of

the spools and that portion of the ribbon in the vibrator with the field *a* at the top or nearer the printing point than the field *b* or red field. It will be observed, from an inspection of Fig. 3, that the ribbon passes in 70 front of the body portion of the guide part 34 and in front of the upper ends of the arms 49 of the trunnion plate. If now the printing keys be operated, their associate type bars will be operated to cause the types to 75 coöperate with said platen through the printing opening 53 in the vibrator. The parts are so proportioned and arranged that at each key depression, before the associate type bar reaches the platen, the ribbon 80 vibrator, through the connections comprising the bell crank 69, link 72, bell crank 75, rod 80 and universal bar 22 will be moved upward to interpose the upper portion or field *a* of the ribbon between the type and the paper 85 on the platen. The throw or upward movement of the vibrator is unvarying. Consequently as the spring drum 20 moves intermittently under the control of the escapement devices to feed the platen a letter space 90 distance at a time, and as the ribbon is thereby caused to be fed longitudinally from spool to spool through the train of mechanism comprising the pinion 33 connected with said spring drum, the pinion 32, a pinion 29 and 95 a pinion 28, the type impressions will describe a straight path longitudinal of the field *a* of the ribbon.

When it is desired to employ the lower or 100 red field *b* of the ribbon, the crank handle 88 is pressed rearwardly to rotate the crank rod 81 through half a revolution. As the crank rod is turned rearwardly, the lower portion of the guide part 34 is swung away from the face of the supporting part 35 of the vibrator, carrying with it the trunnion plate 47 which will be swung about the upper edges of the lugs 57 as pivots and will press the spring tongue 56 forwardly. As the lower portion of the part 34 is swung forwardly 105 away from the part 35 the upper portion of said part 34 will slide down over the face of the part 35, being maintained in contact with said face by the pressure of the spring tongue 56.

An intermediate position of the parts is represented in full lines in Fig. 2 of the drawings. It will be clearly understood from an inspection of said figure that on the completion of the half revolution of the crank rod 120 81, the part 34 of the vibrator will have assumed the position shown in the dotted lines in said Fig. 2, with the outer faces of the arms 38 and 39 pressed against the front of the part 35 by the spring tongue 56 acting 125 through the trunnion plate 47, while the normal rearmost face of the body portion of the part 34 will be in view of the operator, the ribbon passing behind said face and also behind the upper ends of the arms 49 of the 130

trunnion plate as well as behind the inner end of the crank arm 81. It will be understood that the off-set portion 83 of said crank arm will now be in its lowermost position so that that portion of the ribbon between the left-hand spool and the vibrator will not be interfered with by the crank rod 81. By this reversal the guide part 34 of the vibrator, portions of the ribbon between the 10 spools and said vibrator have been twisted reversely and that part of the ribbon in the vibrator will also have been reversed so that the stripe *b* will now be uppermost and nearer the printing point, while the stripe *a* 15 will be lowermost, that side or face of the ribbon which previously faced the paper and was pressed against it under the action of the types being now outermost and in view of the operator; while that side or face 20 which was then outermost now faces the paper. Consequently as the printing instrumentalities are operated as hereinbefore explained, the ribbon vibrator will be reciprocated back and forth to bring the field *b* in operative position and the type impressions will describe a path longitudinal of said field *b*. When it is desired to again employ the black field *a* of the ribbon, the operation above described may be reversed and the 25 part 34 of the vibrator may be turned back to normal position. The term normal position as applied to the part 34 has been used for convenience as applying to the position of said part first described, as illustrated in 30 Figs. 1 and 2.

Although my reversible ribbon carrier or vibrator is particularly well adapted for use with a polychrome ribbon it is not limited to such use, and as I have heretofore stated, 40 it may be advantageously employed in connection with a ribbon having uniform characteristics throughout in order to more thoroughly exhaust the inking surface of the ribbon than has been possible with such ribbon vibrators as have been heretofore employed having a uniform and unvarying vibratory movement or throw. Whether the ribbon be a polychrome ribbon or a ribbon 45 having uniform characteristics throughout, it will be understood that in one position the vibrator moves the ribbon so that one side of one longitudinal portion of the width of said ribbon will be caused to coöperate with the printing instrumentalities, and when 50 said vibrator is reversed or turned the other side of said ribbon will coöperate with said printing instrumentalities along another and different longitudinal portion of the ribbon. The normal position of that part of the ribbon 55 within the vibrator is the same before and after said vibrator has been reversed; that is, the edge of the ribbon which is uppermost is always in the same relation normally with the printing point on the platen. 60 It will be seen, therefore, that I provide 65

means for adjusting the ribbon vibrator to enable different portions of the width of the ribbon to coöperate with the printing instrumentalities without altering the width-wise relation of the ribbon with the printing 70 line, and that though said vibrator is moved an unvarying distance and always brings the upper portion of the width of the ribbon to the printing position, yet by my invention I provide means for adjusting said vibrator 75 so that both the upper and lower portions of the width of the ribbon may be used and the inking surface thereby uniformly exhausted.

Various changes may be made in the construction of the parts to adapt them to other 80 structures or for simplifying or otherwise modifying the constructions herein shown and described, and the parts may be arranged and combined otherwise than as herein shown, all without departing from 85 the spirit and scope of my invention.

What I claim as new and desire to secure by Letters Patent, is:—

1. In a typewriting machine, the combination of a platen; printing instrumentalities; 90 means for feeding the ribbon longitudinally; a ribbon carrier; means for adjusting the ribbon carrier to enable different portions of the width of the ribbon to coöperate with the printing instrumentalities without altering 95 the normal distance between the ribbon and the printing line on the platen; and means independent of the adjusting means for invariably giving the ribbon carrier a uniform movement at printing operations. 100

2. In a visible writing machine, the combination of a platen; printing instrumentalities; means for feeding the ribbon longitudinally; a ribbon vibrator having a fixed 105 normal position in which the ribbon is always normally maintained at an unvarying distance away from the printing point; means for moving said ribbon vibrator to and from the platen at printing operation, the movement or "throw" given to the vibrator 110 by said moving means being uniform; and means for adjusting said vibrator to enable different portions of the width of the ribbon to coöperate with the printing instrumentalities. 115

3. In a typewriting machine, the combination of a ribbon carrier that is reversible to present either side or face of the ribbon to the paper; and means for invariably giving the ribbon carrier a uniform movement at 120 printing operations.

4. In a typewriting machine, the combination of a ribbon carrier; and means for adjusting the ribbon carrier to change its normal position and enable either side or face of 125 the ribbon to be written upon at will.

5. In a typewriting machine, the combination of ribbon spools; means for rotating said spools to feed the ribbon longitudinally; a ribbon carrier; and means for adjusting 130

said ribbon carrier to change its normal position and enable either side or face of the ribbon to be written upon at will without transposing or reversing said spools.

5 6. In a typewriting machine, the combination of a platen; printing instrumentalities; means for feeding the ribbon longitudinally; a ribbon carrier; and hand operated means for adjusting the ribbon carrier to change its 10 normal position so as to enable either side or face of the ribbon at will to coöperate directly with said printing instrumentalities.

7. In a typewriting machine, the combination of a platen; printing instrumentalities; 15 means for feeding the ribbon longitudinally; a ribbon carrier adjustable to position one-half of one side or face of the ribbon to coöperate with the printing instrumentalities and to position the opposite half of the other 20 side or face of the ribbon to coöperate with said printing instrumentalities; and means for giving a uniform movement to the carrier from either adjusted position at printing operation.

25 8. In a typewriting machine, the combination of a platen; printing instrumentalities; a ribbon vibrator; means for automatically moving said ribbon vibrator an unvarying distance from a fixed normal position at each 30 printing operation so as always to bring a portion of the width of the ribbon which is at a fixed distance from an edge and from the center thereof to cover the printing point and coöperate with the printing instrumentalities; and means for adjusting said vibrator 35 so that either portion of the width of the ribbon from the center to an edge thereof may be used.

9. In a typewriting machine, the combination 40 of a two-part ribbon carrier, one of the parts being reversible to present either side or face of the ribbon to the paper; and means for invariably giving a uniform movement to said carrier at printing operation.

45 10. In a typewriting machine, the combination of a two-part ribbon carrier; connections between the two parts, said connections enabling one of said parts to be reversed with respect to the other part; and means for 50 invariably giving a uniform movement to said carrier at printing operation.

11. In a visible writing machine, the combination of a ribbon vibrator comprising a 55 rotary ribbon guiding part and a reciprocating part for supporting said ribbon guiding part; and means for varying the normal position of said rotary part by turning said rotary part on said supporting part to employ different widthwise portions of the ribbon.

60 12. In a typewriting machine, the combination of a ribbon carrier comprising a ribbon guiding part and a supporting part, the two parts being pivotally connected and the guiding part being rotatable on the other to 65 vary the normal relationship between the

two parts so as to enable different portions of the width of the ribbon to be brought into use.

13. In a typewriting machine, the combination of a ribbon carrier comprising a ribbon 70 guiding part and a supporting part, the two parts being pivotally connected and the guiding part being reversible on the other to vary the normal relationship between the two parts; and means for maintaining the 75 two parts in either of their relations.

14. In a typewriting machine, the combination of a ribbon carrier comprising a ribbon guiding part and a supporting part, the two parts being pivotally connected and the 80 guiding part being reversible on the other part; hand operated means connected with said guiding part and adapted when operated to reverse said guiding part; and means for maintaining the two parts in either of their 85 relations.

15. In a typewriting machine, the combination of a ribbon carrier comprising two parts, one of said parts being provided with ribbon guiding slots; a connecting member 90 pivoted to said slotted part and having a spring-pressed connection with the other of said parts, whereby the two parts are maintainable in fixed relations; and hand operated means for turning said part on its pivot 95 in order to reverse it.

16. In a typewriting machine, the combination of printing instrumentalities; a two-part vibrator, one part of which is connected to receive a vibratory movement during 100 actuation of the printing instrumentalities and the other part of which is carried by and pivoted to the vibratory part; and hand actuated means independent of said printing instrumentalities for turning said pivoted 105 part of the vibrator to present different widthwise portions of the ribbon to the action of the printing instrumentalities.

17. In a typewriting machine, the combination of printing instrumentalities; a two-part vibrator, one part of which is connected to receive a vibratory movement during actuation of the printing instrumentalities and the other part of which is carried by and pivoted to the vibratory part; a spring which 110 tends to maintain the two members of the vibrator in a fixed relation; and hand actuated means for turning the pivoted member of the vibrator to present different widthwise portions of the ribbon to the action of 115 the printing instrumentalities.

18. In a typewriting machine, the combination of a ribbon carrier comprising two parts, one of said parts being provided with ribbon guiding slots; and a U-shaped connecting member on which said slotted part 120 is journaled and by means of which the two parts of the carrier are connected.

19. In a typewriting machine, the combination of a ribbon carrier comprising two 125

parts, one of said parts being provided with ribbon guiding slots; a U-shaped connecting member on which said slotted part is journaled; and means for causing a pivotal movement of the U-shaped connecting member on the other part of the carrier.

20. In a typewriting machine, the combination of a ribbon carrier comprising two parts, one of said parts being provided with ribbon guiding slots; a U-shaped connecting member on which said slotted part is journaled; means for causing a pivotal movement of the U-shaped connecting member on the other part of the ribbon carrier; and a spring secured to the latter part and co-operating with the U-shaped connecting member and tending to maintain the two parts of the ribbon carrier in fixed relation.

21. In a typewriting machine, the combination of a ribbon carrier comprising two parts, one of said parts being provided with ribbon guiding slots; a U-shaped connecting member on which said slotted part is journaled, the base of said U-shaped part resting on lugs projecting from the face of the other of said ribbon guiding parts, a spring secured to the latter part and constantly pressing against said connecting member so as to maintain the two parts of said ribbon carrier in a fixed relation; and a rod journaled on the frame of the machine, one end of said rod being connected with the slotted part of said guide and the other end of said rod being provided with a crank arm for turning said rod and reversing said slotted part.

22. In a typewriting machine, the combination of a ribbon carrier comprising two parts, one of said parts being provided with ribbon guiding slots and having trunnions; a U-shaped trunnion plate on which said trunnions are journaled, the base of said member resting on lugs projecting from the face of the other of the parts of said ribbon carrier; a spring adapted to maintain the two parts of said ribbon carrier in contact with each other; and a rod pivoted on the frame of the machine and pivotally connected at one end with one of said trunnions, the other end of said rod being provided with a crank arm operable from the side of the machine for turning the rod and reversing the slotted part of said ribbon guide.

23. In a visible writing machine, the combination of a bracket secured to the frame of the machine; a two-part ribbon vibrator comprising a slotted guide part normally maintaining the ribbon away from the printing point and a holding part for said guide part having a sliding connection with said bracket; a connecting member pivotally connected with said holding part and with said guide part; a spring pressing the two parts of said vibrator together, said guide part being reversible on said holding part; and means for communicating reciprocal motion to

said holding part to move said guide part to and from the printing point at printing operation.

24. In a visible writing machine, the combination of a bracket secured to the frame of the machine; a two - part ribbon vibrator comprising a slotted guide part normally maintaining the ribbon away from the printing point and a holding part for said guide part having a sliding connection with said bracket; a connecting member pivotally connected with said holding part and with said guide part; a spring pressing the two parts of said vibrator together; a rod pivotally connected with said guide part and operable from the side of the machine to reverse said guide part; and means for communicating reciprocal motion to said holding part to move said guide part to and from the printing point at printing operation.

25. In a typewriting machine, the combination of a platen; printing instrumentalities; a pair of ribbon spools, one at either side of the machine; and means independent of said printing instrumentalities for reversing or turning that portion of the ribbon which is between the spools so as to enable either side or face of the ribbon to coöperate with the printing instrumentalities.

26. In a typewriting machine, the combination of a platen; printing instrumentalities; a pair of ribbon spools, one at either side of the machine; means for rotating said spools to communicate longitudinal movement to the ribbon; and means independent of said printing instrumentalities for turning or reversing that portion of the ribbon between the ribbon spools, whereby either side or face of the ribbon may be caused to co-operate with the printing instrumentalities, one portion of the width of the ribbon being employed when one face of said ribbon is in coöperative position and another portion of the width of the ribbon being employed when the opposite face of the ribbon is in coöperative position.

27. In a typewriting machine, the combination of a platen; printing instrumentalities; a pair of ribbon spools, one at either side of the machine; means normally maintaining one side or face of the ribbon in coöperative relation with said printing instrumentalities; and means operative on said first recited means to bring the other side or face of the ribbon into coöperative relation.

28. In a visible writing machine, the combination of a platen; printing instrumentalities, means for feeding the ribbon longitudinally; a ribbon vibrator normally maintaining the ribbon away from the printing point at a fixed normal position; means for moving said vibrator an unvarying distance at printing operation so as always to bring the upper portion of the width of the ribbon to cover the printing point and coöperate

with the printing instrumentalities; and means for adjusting said vibrator so that both the upper and lower portions of the width of the ribbon may be used.

- 5 29. In a typewriting machine, the combination of printing keys; a ribbon guide adapted to turn on a pivotal axis substantially coincident with the longitudinal center of the ribbon; means independent of 10 said printing keys for turning said ribbon guide on said pivotal axis; and means for giving a uniform vibratory movement to said ribbon guide when said printing keys are operated.
- 15 30. In a typewriting machine, the combination of a ribbon vibrator; means for automatically actuating said vibrator at printing operation; and hand operated means for turning said vibrator on a pivotal axis substantially coincident with the longitudinal 20 center of the ribbon.

31. In a typewriting machine, a slotted ribbon guide comprising two sets of arms folded over from the sides of the guide, one set of arms projecting downwardly and the other set upwardly and the companion arms having diagonal parallel edges flush with each other.

32. In a typewriting machine, the combination of a ribbon vibrator, means for moving the vibrator always in the same path to and from the printing point; and means for reversing the vibrator.

Signed at the borough of Manhattan, city of New York, in the county of New York, and State of New York, this 27th day of January, A. D. 1906.

ANDREW W. STEIGER.
